UNITED STATES PATENT OFFICE.

GRANVILLE W. WRIGHT, OF NEW HAVEN, CONNECTICUT, ASSIGNOR TO
THE UNITED STATES HARDWARE COMPANY, OF SAME PLACE.

DESIGN FOR A TOY.

SPECIFICATION forming part of Design No. 28,551, dated May 3, 1898.

Application filed May 8, 1897. Serial No. 635,742. Term of patent 31 years.

To all whom it may concern:

Be it known that I, GRANVILLE W. WRIGHT, a citizen of the United States, residing at New Haven, county of New Haven, and State of Connecticut, have invented and produced a new and original Design for a Toy, of which the following is a specification, reference being had to the accompanying drawings, forming part thereof.

10 Figure 1 is a plan view of a toy embodying my design. Fig. 2 is a side view thereof.

As shown in the drawings, the leading feature of my design consists in the representation of a pleasure or racing boat resting upon 15 a four-wheeled truck and containing a series of oarsmen in position for rowing and grasping an oar.

The letter A designates the boat-shaped

body; B, the series of figures representing oarsmen; C C, the two series of oars projecting from opposite sides of the body A, and D D D D the four wheels of the truck.

The several parts constituting the design may have any desired distinctive color.

Having thus fully described my invention, 25 what I claim as new, and desire to secure by Letters Patent, is—

The design for a toy substantially as herein shown and described.

In testimony whereof I have hereunto affixed my signature this 6th day of May, 1897.

GRANVILLE W. WRIGHT.
